UNITED STATES PATENT OFFICE.

AUGUSTUS G. BURTON, OF CHICAGO, ILLINOIS, ASSIGNOR TO CHAS. E. DAVIS
AND JOHN W. NORRIS, OF SAME PLACE.

CLAY-SEAL-MAKING MACHINE

SPECIFICATION forming part of Letters Patent No. 444,232, dated January 6, 1891.

Application filed October 14, 1889. Serial No. 327,034. (No model.)

To all whom it may concern:

Be it known that I, AUGUSTUS G. BURTON, a citizen of the United States, residing at Chicago, county of Cook, and State of Illinois, have invented certain new and useful Improvements in Seal-Making Machines, which are fully set forth in the following specification, reference being had to the accompanying drawings, forming a part thereof.

10 This invention consists of improvements upon a seal-making machine designed by Christian C. Hill, and described in his application, numbered 328,446, filed in the Patent Office October 28, 1889.

15 The improvements relate to means for numbering the seals consecutively and for inking the imprinting mechanism and for delivering the seals when completely formed and imprinted upon a suitable tablet or tray for 20 transportation to the drying-oven.

In the drawings, Figure 1 is a front elevation of the seal-making machine, the details which do not pertain to my improvement being omitted, except in so far as it is necessary 25 to show them to make clear the relation of my improvement to the remainder of the machine. Fig. 2 is an enlarged detail section of a portion of the tray and the delivering mechanism. Fig. 3 is an enlarged detail rear elevation of the same parts, showing also a portion 30 of the bearing of the actuating-shaft and cam thereon and lever and connecting-rod whereby the necessary motion is imparted to the delivering mechanism. Fig. 4 is a detail 35 plan of the imprinting and part of the adjacent mechanism. Fig 5 is a section at 55 on Fig. 4. Fig. 6 is a detail sectional elevation of the crank and cam mechanism which operates the inking-roll. Fig. 7 is a detail sec-

40 tional elevation of the feed-operating eccentric and lever, the position being that which corresponds to the full-line position of the ink-roll-operating mechanism in Fig. 6. Fig. 8 is a detail front elevation of the stamp-head-operating crank and link, and a cam on the 45 same shaft which operates the cutting and delivering mechanism, the position corresponding to that of the full lines in Fig. 7. Fig. 9 is a detail section at the line 99 on Fig. 50 4. Fig. 10 is a bottom plan of the inking-plate-rotating devices.

A is the frame of the machine; B, the conveyer-belt which receives the clay tape from which the seals are formed and transports it under the imprinting and dividing mechanism.

55 C' is the actuating-shaft of the imprinting mechanism journaled in the bracket A', which is supported on the main frame A and affords the vertical guide-bearings for the vertically-reciprocating head C², to which are secured the seal-imprinting stamp C²⁰ and the numbering mechanism C²¹. This head is actuated in the familiar manner of power by a crank c¹⁰ on the shaft C' and a link c¹¹, connecting said crank to the head C².

60 I will now describe the mechanism for inking the stamping devices. Upon the shaft C' there is made fast the collar C³, Fig. 4, having a laterally-projecting stud C³⁰, and 70 upon the upper end of the bracket A', above the bearing of the shaft C', there is secured the supplemental bracket A¹⁰, having journal-boxes a¹⁰ a¹⁰ for the rock-shaft C⁴. To the rear end of this rock-shaft there is secured 75 the lever-arm C⁴⁰, which overhangs the shaft C', and beyond the latter has secured to it the cam C⁴¹, Figs. 4 and 6. This comprises, as a cam-track exposed to the action of the stud C³⁰, the straight lower edge c⁴⁰ and 80 the downwardly-concave curvilinear edge c⁴¹, which makes nearly a right angle with the straight edge c⁴⁰. As the shaft C' revolves, the stud C³⁰, coming up under the cam C⁴¹, encounters the straight edge c⁴⁰, and as 85 the stud continues to revolve upward it lifts the cam C⁴¹ and the lever-arm C⁴⁰, rocking the shaft C⁴. The stud encounters the straight edge c⁴⁰ near the farther corner, and as it rises travels across that edge to the corner formed by that edge and the concave edge c⁴¹, continuing to lift the cam during so 90 much of its revolution. The stud reaches the corner c⁴² after it has passed the horizontal plane of the shaft C', and at this position the lifting action ceases, (see Fig. 6,) because the stud running off the edge c⁴⁰ and coming into contact with the concave edge c⁴¹, revolving upward and coming back toward the vertical plane of the shaft, withdraws from under the 95 cam which settles down upon it and descends on account of the shape of the edge c⁴¹, be-

ing in that position eccentric to the shaft, notwithstanding that the stud is still rising in its rotary movement. By the time the stud is vertically over its shaft C' the lever-arm C¹⁰ has dropped down and is stopped upon the shaft itself C', the stud continues revolving out from under the cam C¹¹, and continues its revolution until it again encounters the under edge c¹⁰ of the cam. To the forward end of the rock-shaft C⁴ there is secured the lever-arm C⁵, which actuates the inking mechanism, which will now be described.

To the frame A at the forward edge there are secured two brackets II II, which project upward and afford bearing for the slide-bar II', which reciprocates in them parallel to the course of the carrying-belt. Upon the slide-bar II' are secured two adjustable stops II², for a purpose which will hereinafter be explained. To the frame there is also secured, most conveniently at the rear, a bracket I, which extends up and overhangs the carrying-belt B, and has mounted upon it the revolving ink-spreading plate I'. This spreading-plate has projecting from its lower side the studs i', constituting teeth by which it is actuated by means of a pawl II⁴, pivoted to the end of the slide-bar II'. The pawl engages the tooth i' on the pushing stroke and rotates the plate I' a short distance and slips over the tooth on its return-stroke. The arm C¹² of the shaft C⁴ normally extends downward from said shaft, and near the lower end it is connected to the link C⁶, which extends to the left and downward from said connection and has the cross-bar C⁵⁰, to which there is pivoted the inking-roll arm or frame C⁶. As illustrated, this device is a frame comprised of two side bars C⁶⁰ C⁶⁰, between which the cross-bar C⁵⁰ extends, said side bars extending from the said cross-bar back to the right, and at their extreme end in that direction having journaled in them the inking-roller C⁷, which at its extreme position to the left rests upon the plate I'. To the frame A there is secured a bracket, which has arms A³⁰ extending up and overhanging the conveyer-belt and one of them overhanging the plate I', and in said overhanging arms the bars C⁶⁰ obtain slide-bearings, the position of said arms and bearings therein being such as to permit the bars to slide therein while the roll contacts the inking-plate. The cross-bar C⁵⁰ extends far enough forward to protrude between the stops II² on the slide-bar II' and engage them as it is reciprocated. The action of this mechanism, it will be seen, is as follows: When the rock-shaft C⁴ is rocked by the engagement with the cam C¹¹ of the stud C³⁰, as above described, the lever-arm C¹² will swing to the right, and by means of the link C⁶ will reciprocate in that direction the inking-roller frame C⁶ and the ink-roller C⁷, and assuming those parts to have been at their extreme position to the left when the arm C¹² commenced to swing the inking-roller will be

pushed to the right off from the inking-plate I', and the seal-imprinting and numbering devices being at this time at their highest position said roller will be passed on under them and will ink their downwardly-exposed faces. When the stud C³⁰ passes off the straight edge c¹⁰ onto the curved edge c¹¹ and the lever-arm C¹² begins to descend and the lever-arm C¹² to swing to the left, the inking-roller will be withdrawn, passing again over the downwardly-exposed printing-faces onto the inking-plate I'. In the first motion to the right the cross-bar C⁵⁰ will encounter one of the studs II², and thereby as it moves will reciprocate the bar II' and cause the pawl II⁴ to be pushed against the tooth i' of the plate I' and rotate the plate, and as the reverse motion is nearing its completion just as the inking-roll reaches the edge of the plate said cross-bar will encounter the other stop II² and retract the bar II', the pawl II⁴ slipping over the tooth i', which stands behind it, and being by the controlling-spring 90 caused to engage behind said tooth, ready for the next actuating movement.

I will now describe the mechanism for subdividing the tape into individual seals and for delivering such seals off from the conveyer-belt and piling them on a receiving-tray. To the shaft C', in front of its bearing in the bracket A', there is secured the cam J, which is circular throughout the greater portion of its periphery, having, however, one eccentric prominence J'. To the bracket A', at the lower part, there is pivoted the lever J², extending nearly upright from its pivot and having toward the upper end an abutment J²⁰, preferably being an anti-friction stud and roll projecting horizontally across the plane of the cam J, said abutment J²⁰ contacting the periphery of said cam and being held in contact with said periphery by the spring J³, connected to the upright frame-post A⁴ and to said lever J². To the lever, between the abutment J² and the pivot, there is connected the rod or link I, the other end of which is connected to an arm L' of a rock-shaft L², which is journaled in lugs a' a', which project upward from the frame A, one on each side of the conveyer-belt. Said rock-shaft has another lever-arm L³ extending to the left, nearly horizontal to the end of which there is secured the knife L⁴. To the frame A there is secured in position to overhang the conveyer-belt two plates R, between which there is secured a quantity of felt R', said plates having the slots r, through which the knife L⁴ can descend, the felt being also cut through in the path of the knife, but not having any material removed. The purpose of this felt is to hold a suitable lubricating substance to prevent the knife sticking to the tape when it cuts it, and also to wipe the knife clean as it passes through the felt. The position of the prominence J' on the cam J is such with respect to the position of the crank by which the stamp-head is recipro-

cated that it actuates the lever J^2 while the stamp is down and causes the knife L^4 to descend through the lubricating-felt and to cut the tape which lies on the conveyer-belt 5 transversely, making this motion, as it will be observed, once for each revolution of the shaft C' , and so making a subdivision of the plate as often as an imprint is made upon it by the stamp-head. The tape being the 10 width of two seals, the knife being the width of the tape, severstwo seals therefrom at every stroke, and imprinting-dies are in like manner made double, printing two seals at each descending movement of the stamp-head. 15 From the bearings of the idle-roller q , around which the belt E passes at the delivery end, two lugs S extend obliquely downward and toward the left, and in them is journaled a rock-shaft S' , Figs. 2 and 3, having secured 20 to it between its bearings the lip S^2 , of sheet metal, and having made fast also to it rearward of the rear bearing the pinion S^3 . To the lever J^2 there is connected the link S^4 above the point of connection of the link L , 25 and to the other end of said link a short rack S^{40} is secured, which is adapted to mesh with the pinion S^3 . The link S^4 may be provided with a fixed guide-bearing S^{41} , by which the rack S^{40} is kept in mesh with the pinion S^3 . 30 It will be seen that as the lever J^2 is oscillated by the cam J and the spring J^3 the rack S^{40} will actuate the pinion S^3 and rock the shaft S' back and forth as the lever J^2 moves back and forth. The normal position of the lip 35 S^2 —that is, the position occupied when the prominence J' of the cam J is not in engagement with the abutment J^{20} of the lever J^2 —is projecting upward, its upper edge being just below the plane of the upper surface of 40 the upper ply of the conveyer-belt. To the frame A there is secured a thin strip of metal S^5 , which at its inner edge is in contact with the upper surface of the belt and overhangs the idle-roller q , its delivery edge overhang- 45 ing the upper edge of the lip S^2 when the latter is normally upstanding. Its right-hand edge contacting the belt just where the belt begins to curve as it passes around the roller, the seals carried by the belt will be lodged on 50 the lip and pushed on over, those behind pushing those in front as the belt moves, and as each seal becomes overbalanced as it passes off the delivery edge of the strip S^5 it falls down in front—that is, at the left—of the up- 55 wardly-projecting lip S^2 , lodging edgewise on the tray T , leaning to the right against said lip. Now when the lever J^2 is oscillated, and through the connections described rocks the shaft S' , the lip S^2 is tipped to the left and 60 tips over in that direction the seal which has been leaning up against it. A block or any temporary obstruction or rest being provided on the tray T , against which the first seal thus tipped over may be caused to lean to the left, all subsequently-delivered seals will 65 be caused to lean up against the preceding one, and as the tray is carried to the left by

the chain V a distance corresponding to the thickness of the seals they will be piled thereon, standing on edge in convenient shape 70 to be subsequently handled. The tray or tablet is carried by endless chains driven around sprocket-wheels $V' V'$, actuated by pawl-and-ratchet mechanism connected with the lever F' . This mechanism is the same as 75 that shown in said application of Christian C. Hill, filed October 28, 1889, Serial No. 328,446.

The numbering-machine C^{21} may be of any familiar construction and is not herein illustrated in detail. It is sufficient to say that 80 the numbering mechanism consists of the number-wheels, of which one is shown, (indicated by the letter U'), and that this mechanism is actuated at each reciprocation of the head to change the number, the actuation being effected by the collision of the plunger-head U^2 of the numbering-machine with the abutment or stop U^3 as the head rises, said abutment being made fast to the bracket A' behind the head and extending out past it, so 85 as to overhang the plunger U^2 . The numbering-machine is located to the right of the seal-imprinting stamp a distance such that its numeral-type faces stand one or more seal-lengths from the space left for the number in 90 the seal-imprint stamp, so that as the tape advances it first receives the number and afterward the seal-imprint, a following seal being numbered while the first is receiving the seal-imprint. 100

The inking mechanism is necessarily constructed in view of the fact that the roll must travel horizontally over both the seal-imprint stamp and the numbering-stamp, this necessity compelling the provision for a long horizontal stroke, such as the described mechanism affords. 105

I claim—

1. In combination with the conveyer-belt, the receiving-tray located below the level of it at the delivery end, mechanism which actuates the tray longitudinally intermittently a distance corresponding to the thickness of the seals at each impulse, the lip S^2 , pivoted to the frame and normally upstanding from its pivot at the delivery end of the belt, and mechanism which rocks it from its position of rest outward slightly past the vertical position after each impulse of the tray-actuating mechanism, substantially as and for the purpose 115 set forth.

2. In combination with the conveyer-belt, the receiving-tray located below the level of it at the delivery end, the lip S^2 , pivoted to the frame and normally upstanding from its pivot at the delivery end of the belt and adapted to be rocked on its pivot outward from the belt, substantially as and for the purpose set forth. 125

3. In combination with the conveyer-belt, the receiving-tray located below the level of its carrying-surface at the delivery end, the fixed lip S^5 , secured to the frame overhanging the delivery end of the conveyer-belt and hav-

ing its inner edge close thereto, and the lip S²,
pivoted to the frame and normally upstanding
from its pivot and overhung at its upper end
by the outer edge of the fixed lip S³ and adapted
5 to be rocked over its pivot outward from the
delivery end of the conveyer, substantially as
and for the purpose set forth.

In testimony whereof I have hereunto set

my hand, in the presence of two witnesses, at
Chicago, Illinois, this 5th day of September, 1889.
